CLAIM

The ornamental design for a pickleball paddle as shown and described.

DESCRIPTION

FIG. 1 is a front, side perspective view of a pickleball paddle;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines depict portions of the pickleball paddle that are environmental and form no part of the claimed design. The dot-dash broken lines depict the boundaries of the claimed design and form no part thereof.
